UNITED STATES PATENT OFFICE

2,589,568

DIFFUSION APPARATUS

André Jean Pierre Olier, Laure, France, assignor
to Societe Anonyme des Etablissements A. Olier,
Clermont-Ferrand, France, a French company

Application November 29, 1949, Serial No. 130,049
In France April 21, 1948

9 Claims. (Cl. 127—7)

1

It is well known that in the sugar industry so-called continuous diffusion apparatuses may be used in order to extract from beets cut into slices or chips the sugar juice contained therein.

Such apparatuses essentially comprise a unit of vertical conduit (or column) elements which are connected together through bent connecting pieces and in which an endless mechanical conveyor carries the chips at a uniform rate in contact with a liquid of treatment circulating in the opposite direction, said liquid being used for the purpose of extracting through diffusion the sugar contained in said chips. The endless mechanical conveyor is preferably formed of a series of perforated transversal discs or plates carried by two endless parallel chains or other bonds guided through loose pulleys. In the case of a chain conveyor said pulleys are provided with teeth the pitch of which corresponds to the pitch of the chain.

During the operation, the chains may take a certain play owing either to the elongation of the chains themselves or to the wear of the rotary parts such as pulleys, axes, bearings and the like. The presence of this harmful play may entail serious deteriorations such as catchings or breakings of the conveyor.

The present invention has for its object an improved continuous diffusion apparatus for the sugar industry or the like which makes it possible to avoid the above mentioned disadvantages.

The invention has more particularly for its object a continuous diffusion apparatus which comprises means through which the rope or ropes, chains or other bonds of the endless conveyor which carries the substances to be treated may be tensioned directly.

The invention has also for its object a continuous diffusion apparatus wherein one at least of the elements of the endless conduit is movable vertically and acts under the action of its own weight and of the weight of the materials which it contains as an automatic tensioning device for the ropes, chains or other bonds of the endless conveyor.

The movable conduit element may be with advantage U-shaped, both legs of the U being mounted slidably in a vertical direction in the adjacent extremities of the stationary remainder of the endless conduit.

This arrangement makes it possible to avoid the necessity of a permanent surveillance of the apparatus which thus works under the optimum conditions of regularity and safety.

Furthermore, the movable element of the con-

duit is, as a matter of fact, an additional element which extends the total length of the endless treatment circuit so that the extraction by diffusion is more complete because of the larger development of the wetted surface owing to the increase in length of the treatment circuit. Thus, a richer and pure extraction juice is obtained.

Other features and advantages of the invention will appear from the following description.

10 In the accompanying drawing which is given by way of example:

Fig. 1 is a diagrammatical front elevational view showing an improved continuous diffusion apparatus in accordance with the invention.

15 Fig. 2 is a sectional view taken along line 2—2 of Fig. 1.

Referring to the example shown and more particularly to Fig. 1, the continuous diffusion apparatus comprises a series of vertical columns

20 formed of conduit elements 1 assembled at 1^a. The outermost columns 2^a and 2^b and the intermediary columns are connected through tubular connecting pieces 4 shown in a part median sectional view. On both outermost columns 2^a and

25 2^b rests a box 5 shown in a median sectional view and formed of metallic elements 6 assembled at 7. Box 5 comprises two end pieces 8 and 9 in its lower part. The unit formed of the columns and of the head constitutes the stationary part

30 of the circuit. The movable part of the circuit is formed of a conduit element 11 which is U-shaped and comprises, for example, two column elements 12 and 13 connected through a connecting piece 14 similar to connecting pieces 4.

35 The free ends of elements 12 and 13 are provided with flaring spouts 15 and 16 in which the lower ends of end pieces 8 and 9 are inserted with some play.

The stationary and movable parts of the circuit are made fast with each other through an endless conveyor formed, in a known manner, of discs 17 assembled at the ends of a diameter through side chains (or ropes) only one of which is shown at 18 in the drawing, the second being 45 behind the first one in a plane perpendicular to the figure. Said endless chains, the path of which is represented through an interrupted axial line 19, rest on both series of wheels 20 keyed two by two on axes 21 so as to provide between them

50 a space which is sufficient for the free passage of discs 17. Axes 21 rotate in bearings provided in the side walls of the connecting pieces 4 and box 5. The outermost wheels 21^a and 21^b of the stationary part of the circuit are arranged so

55 that the discs (which are indicated at 17^a) may

exactly engage the end pieces 8 and 9. The chains of the conveyor pass below wheels 20 of connecting piece 14 and thus support the movable part 11 of the circuit and maintain spouts 15 and 16 around the lower ends of end pieces 8 and 9.

Connecting piece 14 of the movable conduit element 11 comprises two side brackets 14^a and 14^b each provided with at least one tubular guiding member shown at 22 and 23 respectively. Said guiding members slide on a certain number of small columns 24, 25 secured for example, on side brackets 26, 27 of a lower connecting piece 28. Compression springs 29 and 30 are arranged between brackets 14^a, 14^b and adjusting nuts 24^a, 25^a are screwed onto externally threaded parts 15 of small columns 24, 25.

The chain conveyor is driven, for example, through an electric motor (not shown) actuating one of the pairs of wheels 20, the conveyor moving, for example, in the direction shown by 20 the arrows.

The feeding device consists in a feeder 31 over which a charging conduit 32 is mounted through which the chips are introduced; a photo-electric cell 33 and a source of light 34 are arranged on both sides of conduit 32 opposite inspection windows which are transparent to the flux of light 35 sent out through source 34. Cell 33 is combined as well known per se with a relay (not shown) provided in order to stop the motor driving the conveyor in case, the charging of conduit 32 being interrupted, the flux of light 35 reaches cell 33 and renders it conducting.

The extracting liquid, water, for example, is brought through a tube 36 opening into outlet tube 37 of an output regulator 38 of any current type which controls the opening of an inlet valve 39 on tube 36. The outlet tube 37 of the regulator is connected at 40 to the upper part of the outermost column 2^a so that the extracting liquid flows by gravity in a direction contrary to that of the moving conveyor.

The recovery of the liquid rich in sugar is effected owing to a device for taking liquid mounted on the outermost column 2^b on a level lower than the level of the connecting piece 40 for the inlet of the extracting liquid. As shown in Fig. 2, said device consists at least of a box 41 secured to the side of a conduit element 1 of column 2^b. The wall which separates the column 50 from box 41 is perforated at 42 in order to form a depulping grating or filter through which the sugar juice passes. A tube 43 which is open in its upper part is secured in the axis of the box and leads in its lower part to a suitable vessel 44 in which the sugar juice is collected. Since the liquid cannot flow through the wheel which is mounted above column 2^b, it is necessary, if it is desired to treat the fresh chips which circulate in the movable conduit 11, to recycle the liquid collected at 41 into the portion of the movable circuit which is formed of conduit 11.

To this end, vessel 44 comprises in its lower end a pipe nozzle 44^a which communicates with a pump 45 capable of delivering the liquid from vessel 44 through a conduit 46 and a preheater 47 of an electric or other type into a conduit 48 terminating in three nozzles 49, 50, 51 provided with valves 52, 53, 54 and opening above column 2^b and each of branches 12 and 13 of movable conduit 11 respectively. Through the play of the above mentioned valves it is possible to recycle the preheated sugar juice into a portion of the circuit which corresponds to chips which are still rich in sugar. Branch 12 which directly receives 75

the fresh chips comprises a device 55 for taking liquid identical with that shown in Fig. 2. Said device 55 feeds a conduit 56 leading to a vessel 57 in which the recycled sugar juice is collected the sugar content of which is higher than that of the juice collected at the tap 41.

The operation of the apparatus is as follows:

The charging of fresh chips is effected through feeding conduit 32. Feeder 31 distributes them into the intervals between discs 17^a at their passage on wheel 21^a. The chips move through the following circuit in the direction of the arrows: movable conduit 11, column 2^b, intermediary columns, columns 2^a; in their final horizontal path (before wheel 21^a) the chips fall, exhausted, through an opening 65 into a suitable recovery vessel (not shown). Meanwhile the sugar which they contain dissolved in the extraction liquid introduced at 40 at the top of column 2^a. The liquid which is already rich in sugar is taken out of box 41 through tube 43 and delivered through pump 45 into one at least of nozzles 49, 50, 51 after its passage through preheater 47. The liquid enriched at the maximum is finally collected in box 57.

The chains of the conveyor are tensioned automatically owing to the weight of movable conduit 11 and of the chips contained therein. The tensile stress exerted on the chains may be compensated through compression springs 29 and 30 when the load of conduit 11 is too high. Nuts 24^a and 25^a which are adjustable in height make it possible to adjust the compensating action of the above mentioned springs.

Of course, the improvements in accordance with the invention are not limited to the described diffusion apparatus which was chosen by way of example and they may also be applied to apparatuses which comprise an endless conveyor.

What I claim is:

1. In a continuous diffusion apparatus, more especially adapted for the sugar industry, a conduit forming a closed circuit, on the one hand, for the material to be treated between an inlet opening for the fresh material and an outlet opening for the exhausted material and, on the other hand, for a liquid of treatment between an inlet opening for said liquid and an outlet opening for the liquid enriched in products removed from said material through diffusion, endless flexible conveying means movable in said conduit in order to move said material therein, and one element at least of said conduit being a U-shaped element slideably mounted in the extremities of the stationary remainder of said conduit and movable vertically, and being carried by the axle of a pulley supported by said flexible conveying means, whereby said means are tensioned by the action of the weights of said U-shaped element, and of that of the materials contained therein.

2. A continuous diffusion apparatus as claimed in claim 1 wherein said pulley is concentric to the centre of the bend of said U and below which said conveyor passes.

3. A continuous diffusion apparatus as claimed in claim 1 wherein at least two small guiding columns are provided for guiding said movable conduit element.

4. A continuous diffusion apparatus as claimed in claim 3 wherein springs are arranged on said small columns in order to compensate the excess of tension to which said conveying means is sub-

jected in case of an overload of said movable conduit element.

5. A continuous diffusion apparatus as claimed in claim 1 wherein said closed circuit comprises two outermost vertical columns whose top ends are connected through a horizontal box, and said movable element opens in the lower wall of said box.

6. A continuous diffusion apparatus as claimed in claim 5, wherein said inlet for the fresh material to be treated is arranged at the beginning of the upstream side of said movable conduit element with respect to the direction of movement of the material to be treated.

7. A continuous diffusion apparatus as claimed in claim 6 wherein the extracting liquid circulating in the direction contrary to that of the material to be treated, said outlet opening for the enriched liquid is located on the upstream side of said movable conduit element with respect to the direction of circulation of the extracting liquid, and means are provided for recycling the liquid enriched into said movable conduit element.

10

8. A continuous diffusion apparatus as claimed in claim 7, wherein a depulping grating is arranged on said outlet opening for the enriched liquid.

9. A continuous diffusion apparatus as claimed in claim 7, wherein said movable conduit element comprises a device with a depulping grating for collecting the final liquid.
